E. F. ORR

NOTE SHEET GUIDING DEVICE FOR PLAYER PIANOS AND THE LIKE

Filed Nov. 26, 1923

Inventor:

Edwin Frederick Orr

By Samuel Quincy, Esq.
Attorney.

UNITED STATES PATENT OFFICE.

EDWIN F. ORR, OF NORTH RICHMOND, MELBOURNE, VICTORIA, AUSTRALIA.

NOTE-SHEET-GUIDING DEVICE FOR PLAYER PIANOS AND THE LIKE.

Application filed November 26, 1923. Serial No. 677,031.

To all whom it may concern.

Be it known that I, EDWIN FREDERICK ORR, a subject of the King of Great Britain and Ireland, and a resident of the postal 5 district of North Richmond, a suburb of the city of Melbourne, in the county of Bourke, State of Victoria, Commonwealth of Australia, have invented certain new and useful Improvements relating to Note-Sheet- 10 Guiding Devices for Player Pianos and the like, of which the following is a specification.

A serious defect which at present applies 15 to player pianos and like instruments is the tendency of the perforated note sheet to foul the flanges of the music roll or spool in rewinding. The result is that the note sheets are frequently torn at the edges owing to their engagement with the spool flanges, 20 consequently damaging the note sheets and causing difficulty and inconvenience in the rewinding operation.

In certain makes of player pianos means 25 are provided to guide the sheet whilst it is being unwound for playing. Such guiding means usually comprises a pair of pivoted guiding arms or fingers which press lightly against the opposite side edges of the note sheet and are adapted to control a pneumatic 30 roll shifting mechanism whereby any tendency of the record sheet to move sidewardly out of its proper track causes the music roll or spool to be automatically moved sidewardly in the opposite direction so that the record 35 sheet is thus maintained in its proper central tracking position.

In the rewinding operation however the 40 above device has a distinctly detrimental effect owing to the fact that the roll or spool is moved in the opposite sideward direction to that in which the sheet tends to move. Thus the danger of the spool flange fouling 45 the adjacent edge of the sheet which is tending to move sidewardly out of the proper tracking alignment is emphasized instead of diminished and the edge of the sheet is forced further sidewardly against the adjacent flange, causing the sheet to become crumpled and torn. Furthermore as the 50 rewinding operation is usually effected at a comparatively fast speed, it is more liable to cause damage to the record sheet than the unwinding or playing operation.

The object of the present invention is to 55 overcome the disadvantages referred to by the provision of means to automatically

move the music roll or spool in the same axial or sideward direction as that in which the record sheet tends to move during the 60 rewinding thereof. By such means the flanges of the spool are kept clear of the edges of the note sheet during the rewinding operations and damage to the sheet by fouling said flanges as aforesaid is effectively prevented. 65

Various constructional forms of mechanism may be employed in carrying out the invention: For instance, either pneumatic or purely mechanical or electrical contrivances may be designed to effect the desired 70 result, without departing from the spirit and scope of the invention.

As an example of a suitable constructional embodiment, the desired movement may be effected through the medium of the 75 existing pneumatic roll guiding device above referred to by means of certain alterations and additions to such device as hereinafter described.

Referring to the drawings which form 80 part of this specification:—

Figure 1 is a semidiagrammatic front view showing a practical embodiment of the invention applied to a note sheet guiding device of a well known type. The known 85 parts of the mechanism are indicated in dotted lines whilst the new parts introduced by the invention are illustrated in full lines.

Figure 2 is an elevation on a larger scale 90 of a reversing element or valve which is adapted for insertion in certain pneumatic tubes of existing apparatus as indicated in Figure 1.

Figure 3 is a perspective view of one of 95 the ported discs of the valve seen in Figure 2.

Figure 4 is a perspective view of the other ported disc.

Figure 5 is a plan of Figure 2 the parts 100 being shown in the position occupied during the playing operation.

Figure 6 is a view similar to Figure 5 but showing the parts in the relative positions occupied during the rewinding operation.

In the existing roll guiding or tracking 105 device referred to, the aforesaid pivoted guiding arms 2 engage the side edges 3 of the note sheet 4 and are adapted to control the admission of air into a pair of pneumatic tubes 6 leading to a valve box or vacuum chamber 7 which is in turn connected 110 by two corresponding pneumatic tubes 8

with a pair of bellows 9. This bellows is arranged adjacent one end of the music roll spindle 10 and is connected by a rod 11 with a cam device or pressure member 12 which 5 acts against the opposite end of the music roll spindle 10 to thereby automatically move the roll 13 sidewardly against the influence of a spring 14 and in a sideward direction opposite to that which the note sheet 10 may tend to take during its passage over the tracker bar. Thus, whilst the note sheet is tracking correctly, the bellows 9 remains in equilibrium and the music roll is kept in its proper central position; but should the 15 sheet diverge to either side, the music roll will be automatically moved sidewardly in the opposite direction so that the sheet is thereby maintained in its proper tracking position during playing.

20 In a similar known tracking device, the pneumatic tubes 6 are connected to pairs of supplemental ducts arranged in line with the note ducts of the tracker bar so that whilst the note sheet is tracking correctly, 25 air is admitted equally to the two supplemental ducts of each pair and the bellows 9 remains in equilibrium; but should the sheet diverge to either side during playing, one of said supplemental ducts will be wholly 30 or partially covered by the note sheet and the bellows 9 is thus operated to move the music roll in the opposite sideward direction as aforesaid.

35 The invention may be readily applied to a guiding or tracking device of the above nature by inserting a reversing element such as a rotary or other suitable valve, in either of the pneumatic tube sections 6 or 8 connecting the pivoted guiding arms 2 or the aforesaid supplemental ducts with the bellows which causes the roll to be moved sidewardly 40 as previously mentioned.

45 This reversing element or valve may conveniently consist of a pair of relatively rotatable ported discs 16 and 17, the disc 16 being provided with two ports 18 and 18^a which pass straight through the disc and coincide with nipples 19, 19^a which are preferably connected in the pneumatic tubes 6 as 50 indicated in Figures 1 and 2, said tubes being divided for the purpose. The connecting disc 17 is provided with a pair of straight-through ports 21, 21^a coinciding with nipples 22, 22^a which are also connected 55 to the tubes 6 shown.

60 The disc 16 is also provided in its working face with an additional port 23 which is permanently connected by a passage 24 in the disc with the port 18^a thereof as shown in Figure 3.

65 During the playing operations, the ports 18, 18^a of disc 16 coincide respectively with the ports 21, 21^a of the other disc as in Figure 3 forming a direct passage through the opposite nipples 19 and 22 of one tube and

19^a and 22^a of the other tube 6 so that the aforesaid tracking device operates in the usual manner to move the music roll in the opposite sideward direction to that which the note sheet may tend to take in diverging from its true course. It will be evident however that by turning one of the discs in relation to the other, the port 18 of disc 16 will be moved into alignment with the port 21^a of the other discs, whilst port 18^a will be brought to coincide with port 21 through the port 23 and passage 24. The conditions of operation of the bellows 9 are thus reversed during the rewinding operation so that in the event of the note sheet diverging to one side during such operation, the music roll 13 will be moved in the same sideward direction as that in which the sheet tends to move, instead of in the opposite direction as at present occurs in note sheet guiding devices of the kind referred to. The result is that the edges of the note sheet are automatically kept clear of the spool flanges 13^a during rewinding.

20 The working faces of the discs 16 and 17 may be pressed close against each other by means of a spring 26 encircling a pin or screw 27 which passes through a central hole 28 in each of the discs 16-17. The pressure of the spring 26 may be adjusted by means of nuts 29 on the screw 27.

25 One of the said discs is preferably cut away at 31 to form limit stop faces 32 adapted to be engaged by a pin or projection 33 on the other disc to limit the rotary movement of the latter disc, which movement may be conveniently effected by suitable connections such as a lever 34 and connecting rod 36 extending between the pin or projection 33 on disc 16 and the usual rewinding hand lever 37. Thus by movement of the latter lever in the usual manner to rewind the roll, the normal or playing conditions of communication through the tubes 6, 8 and operation of the bellows 9 are reversed owing to the operation of the reversing element or valve constituted by the ported discs 16, 17.

30 The invention may be thus readily applied to existing instruments in the manner mentioned, or by various other arrangements whereby the music roll or spool is shifted sidewardly with instead of against the note sheet during rewinding.

35 It will be understood that such sideward movement of the music roll or spool is only slight; but any excessive sideward pressure of the note sheet causes the latter and the spool to be automatically moved back together in the opposite direction and thus maintained in proper central position with the edges of the sheet clear of the spool flanges. It will moreover be evident from the foregoing description that various arrangements of mechanism may be employed

in carrying out the invention, which latter resides primarily in the provision of means to automatically move the music roll or spool sidewardly in accordance with and in the same direction as the sideward movement or pressure of the note sheet, to thereby prevent the edges of the sheet from fouling the spool flanges during the rewinding operations.

10 Having now described my invention what I claim as new and desire to secure by Letters Patent is:—

1. In a player piano or the like, the combination with a music roll mounting adapted to permit axial movement of said roll; of means whereby the music roll is automatically moved axially in the same direction as that which the note sheet may tend to take during rewinding of the sheet.

20 2. In a player piano or the like, the combination with means for automatically moving the music roll axially in the opposite direction to that which the note sheet may tend to take during the playing operation; of means whereby said roll is moved axially in the same direction as that which the note sheet may tend to take during the rewinding operation.

3. In a player piano or the like, the combination with a flanged music roll mounted to move in an axial direction, of means controlled by the travel of the note sheet to automatically move said roll axially in the same direction as that which the note sheet may tend to take in diverging from its proper longitudinal course during the rewinding operation.

4. In a player piano or the like, the combination of a flanged music roll mounted to move axially; and pneumatic means controlled by the travel of the note sheet to automatically move said roll axially in the same direction as that which the note sheet may tend to take during the rewinding operation.

5. In a player piano or the like, a pneumatic device controlled by the travel of the note sheet to automatically move the music roll axially in the opposite direction to that which the note sheet may tend to take during the playing operation; and means for reversing the action of said pneumatic device, whereby it moves said roll axially in the same direction as that which the note sheet may tend to take during the rewinding operation.

6. In a player piano or the like, the combination with a flanged music roll mounted to move axially, and a bellows adapted to impart such axial movement to the roll; of means associated with said bellows whereby the latter moves the music roll axially in the same direction as that which the note sheet may tend to take during the rewinding operation.

7. In a player piano or the like, the combination with a bellows adapted to move the music roll axially in the opposite direction to that which the note sheet may tend to take in diverging from its proper tracking course during the playing operation; of means for reversing the action of the said bellows, whereby it causes the roll to move axially in the same direction as that which the note sheet may tend to take during the rewinding operation.

8. In a player piano or the like, the combination with a note sheet guiding device comprising pneumatic tubes the opening of which is controlled by the travel of the note sheet, and means associated with said tubes to automatically move the music roll axially in the opposite direction to that which the note sheet may tend to take during the playing operation; of means interposed in said tubes whereby said roll is moved axially in the same direction as that which the note sheet may tend to take during the rewinding operation.

9. In a player piano or the like, the combination with a bellows operatively connected by pneumatic tubes with the note sheet, whereby any sideward movement of the latter during the playing operation causes the music roll to be moved back axially in the opposite direction; of a reversing device associated with said tubes and bellows, whereby the latter moves the music roll axially in the same direction as that which the note sheet may tend to take during the rewinding operation.

10. In a player piano or the like, the combination with a bellows operatively connected by pneumatic tubes with the note sheet, whereby any sideward movement of the latter during the playing operation causes the music roll to be moved back axially in the opposite direction; of a reversing valve interposed in said tubes between the note sheet and said bellows, whereby the latter moves the music roll axially in the same direction as that which the note sheet may tend to take during the rewinding operation.

11. In a player piano or the like, the combination with a flanged music roll mounted to move axially, and a bellows operatively connected by pneumatic tubes with the note sheet, whereby any sideward movement of the latter during the playing operation causes the music roll to be moved back axially in the opposite direction; of a reversing element interposed in said tubes and operatively connected with the rewinding mechanism of the instrument, whereby said bellows moves the music roll bodily axially in the same direction as that which the note sheet may tend to take during the rewinding operation.

12. In a player piano or the like, the com-

bination with a bellows operatively connected by pneumatic tubes with the note sheet, whereby any sideward movement of the latter during the playing operation causes the 5 music roll to move back axially in the opposite direction; of a reversing valve interposed in said tubes and operatively connected with the manually operated rewinding lever of the instrument, whereby said bellows moves the music roll axially in the 10 same direction as that which the note sheet may tend to take during the rewinding operation.

13. In a player piano or the like, the combination with a note sheet guiding device comprising means operatively connected by pneumatic tubes with the note sheet, whereby any sideward movement of the latter during the playing operation tends to move 15 the music roll back axially in the opposite direction; of a manually operated reversing valve interposed in said tubes, whereby said guiding device may be actuated to automatically move the music roll axially in the same 20 direction as that which the note sheet may tend to take during the rewinding operation.

14. In a player piano or the like, the combination with a note sheet guiding device comprising means operatively connected by 25 pneumatic tubes with the note sheet, whereby any sideward movement of the latter during the playing operation tends to move the music roll back axially in the opposite direction; of a rotary valve interposed in 30 said tubes, and means operatively connecting said valve with the hand actuated rewinding lever of the instrument, whereby said guiding device may be actuated to automatically move the music roll axially in 35 the same direction as that which the note sheet may tend to take during the rewinding operation.

15. In a player piano or the like, the combination with a bellows operatively connected by pneumatic tubes with the note sheet, whereby any sideward movement of the latter during the playing operation causes the music roll to move back axially 40 in the opposite direction; of a rotary valve interposed in said tubes, said valve comprising a pair of oppositely disposed ported

discs arranged face to face and adapted for manual operation, whereby said bellows may be actuated to automatically move the 55 music roll axially in the same direction as that which the note sheet may tend to take during the rewinding operation.

16. In a player piano or the like, the combination with a bellows operatively connected by pneumatic tubes with the note sheet, whereby any sideward movement of the latter during the playing operation causes the music roll to move back axially in the opposite direction; of a reversing valve connect- 60 ed with said tubes, said valve comprising a pair of oppositely disposed discs arranged face to face and adapted for relative rotary motion, each said disc having a pair of ports and nipples which coincide during the 65 playing operation, one of said discs having also an additional port communicating with one of the first named ports of the respective disc; and means for manually operating said valve, whereby said bellows may be 70 actuated to move the music roll axially in the same direction as that which the note sheet may tend to take during the rewinding operation.

17. In a player piano or the like, the combination with a bellows operatively connected by pneumatic tubes with the note sheet, whereby any sideward movement of the latter during the playing operation causes the music roll to move back axially in the opposite 80 direction; of a reversing valve connect- 85 ed with said tubes, said valve comprising a pair of oppositely disposed discs arranged face to face and adapted for relative rotary motion, each of said discs having a pair of 90 ports and nipples adapted to coincide during the playing operation, one of said discs having also an additional port communicating with one of the first named ports of the respective disc; spring means for holding 95 the working faces of said discs in close contact with each other; and an operative connection extending between one of said discs and the rewinding lever of the instrument.

In testimony whereof I affix my signature.

EDWIN F. ORR.
